UNITED STATES PATENT OFFICE.

FRANK A. CRITZ, JR., OF WEST POINT, MISSISSIPPI.

TYPE-WRITER ATTACHMENT.

1,095,960.

Specification of Letters Patent. Patented May 5, 1914.

Application filed April 27, 1912. Serial No. 693,640.

To all whom it may concern:

Be it known that I, FRANK A. CRITZ, Jr., a citizen of the United States, residing at West Point, in the county of Clay and State 5 of Mississippi, have invented a new and useful Improvement in Type-Writer Attachments, of which the following is a specification.

This invention relates to an attachment 10 for typewriters and especially for machines of that type in which the platen has a certain amount of vertical play in combination with a horizontal movement for the purpose of changing from small to capital letters, or where the key basket is shifted for 15 the same purpose.

The object of the invention is to obtain a noiseless shift upon pressure of the shift key without regard to the rapidity or nature of 20 the shifting movement. It will also be understood that this principle can be applied to other movable parts of a typewriter where such part is at present stopped or limited in 25 its movement by striking against a fixed abutment, which is usually in the form of an adjustable screw.

In the accompanying drawings, I have 30 illustrated the invention as applied to the platen, and in said drawings, Figure 1 is an end view of a Royal typewriter with my attachment applied thereto, and the parts in position for writing small letters. Fig. 2 is a similar view, the platen being shifted into position for writing capital letters. 35 Fig. 3 is a perspective view illustrating a preferred form of securing one of the supporting chains.

In these drawings, 1 represents the frame of the machine, 2 the bearings for the platen, 40 3 the platen and 4 one of the pivoted arms supporting the platen frame. These parts are all found upon the Royal typewriter as now in use. This construction I have changed by forming the supporting arms 45 with an eye 4^a at its free end secured to the upper portion of the frame 1 and to the rear of the platen is an angled bracket 5 through the outwardly extending portion of which passes a small eye bolt 6 locked in position by 50 suitable nuts 7. To the eye of said bolt is secured one end of a chain 8, the other end of which engages the eye 4^a and the eye bolt 6 is so adjusted that the chain 8 will be stretched taut and support the arm 4 when 55 the frame 2 and platen 3 are in normal position.

To the frame 1 and below the platen 3 I attach one end of a chain 9, the other end of which also engages the eye 4^a and this chain is normally slack as shown in Fig. 1. 60 The chain 9 is connected at its lower end to a bolt 9^a carried by a bracket 9^b thus making its length adjustable. But when the parts are shifted to the position as shown in Fig. 2 for the purpose of changing from small to capital letters the chain 9 is 65 stretched taut and limits upward movement of the arm 4, stopping it at the proper time, and without the noise which would be caused by said arm striking an abutment. When 70 the parts are returned to normal position the downward movement of the arm 4 is checked by the chain 8 at the proper point and also without noise which would be caused by the said arm striking a second 75 abutment. I therefore provide means for limiting the shifting movement in both directions without causing any of the shifting parts to strike against any fixed portion of the machine.

It will be obvious that this attachment can be applied to various forms of typewriters by simply changing the points of connection of the chains according to the arrangement of the movable parts of the 80 typewriter, and I do not desire to be limited to its use with any particular make of typewriter, or to one in which the platen only 85 is shifted, as it can also be applied in cases where the key basket is shifted instead of 90 the platen.

It is intended by this invention, to provide means for stopping or limiting any part of a typewriter, where such part is movable in the operation of the typewriter 95 and where such movable part heretofore has been limited in its movement by the same coming in contact with a fixed abutment, by a flexible cord, chain or any other flexible material, said limiting or stopping of said 100 movable part being brought about by one end of said flexible material being attached to said movable part and the other end being attached to some fixed part or stationary part of the typewriter, the point of attachment to said movable part, before said movable part is moved, being situated with reference to the said stationary point to which one end of said flexible material is attached, so that the ends of said flexible material will 105 not be so extended as to pull said flexible material taut and said flexible material is so 110

arranged that the length thereof can be so adjusted as to limit said movable part in its proper movement from said fixed point, by said flexible material being drawn taut between said fixed point and said movable part, thus causing the stopping of said movable part to be noiseless. If a chain is used as said flexible material, it should be so made that the ends of each link thereof should be in constant contact with the ends of the links immediately connected to such link.

What I claim is:

1. The combination with a typewriter having a shifting device for the purpose of changing from small to capital letters, of a flexible device fixed at one end to the typewriter frame and secured at the opposite end to said shifting device and normally supporting the same in position for writing small letters, and a second flexible device secured to the frame and also to said shifting device and normally slack, the second men-

tioned flexible device being drawn taut when the parts shift into position for writing capital letters.

2. In a typewriter having a vertically movable platen a pivoted arm adapted to impart such movement, a chain one end portion of which is adjustably secured to a portion of the typewriter frame and the other end of which is secured to the free end of said arm, and a second chain having one end portion also secured to the free end of said arm and the opposite end portion adjustably secured to the frame of the typewriter at a point below the arm, the first mentioned chain supporting the arm in its normal position and the second mentioned chain limiting vertical movement of the arm.

FRANK A. CRITZ, Jr.
